UNITED STATES PATENT OFFICE.

JOHN H. PHILLIPS, OF CHICAGO, ILLINOIS.

ANCHOR-SHELL DRILL.

1,379,210.

Specification of Letters Patent. Patented May 24, 1921.

Application filed July 21, 1919. Serial No. 312,243.

To all whom it may concern:

Be it known that I, JOHN H. PHILLIPS, a citizen of the United States, residing at Chicago, in the county of Cook and State of

5 Illinois, have invented certain new and useful Improvements in Anchor-Shell Drills, of which the following is a description.

My invention belongs to that general class of devices known as stone drills, and relates 10 particularly to a hollow, shell or core type of drill, so constructed as to drill a number of holes in concrete, brick, stone or like material, then to be utilized, with other suitable parts, as an anchor or expansion bolt 15 for fastening and holding various devices and mechanisms to said materials. Anchor or expansion bolts are largely used on ceilings, walls and floors of concrete, brick and stone, for the support of pipe and wire systems, and mechanical, electrical and other equipment, etc. There are many types and sizes of anchor, or as commonly known, expansion bolts, in use, and in the use of any 20 and all types it is first necessary to drill suitable holes to receive them; this requires the use of separate drills of suitable size for the expansion bolt used. This use of separate drills is expensive and unsatisfactory.

In many instances the right size drill is not 25 available, and in many cases the drills used are larger or smaller than should be, and of a type that does not make round or smooth finished holes, thereby failing to give most efficient, workmanlike and economic results.

30 My invention has among its objects the production of a combined drill and shell of the kind described that is simple, convenient, efficient, durable, inexpensive and suitable for use wherever found applicable. My invention has among its further objects the

35 production of a drill shell which may be used as a drill and thereafter utilized, in conjunction with suitable parts, as an anchor or expansion bolt or part thereof in the

40 hole it drilled. The invention has particularly among its objects the production of a device of the kind described embodying both the features of drill and expansion bolt, eliminating the necessity of separate drills 45 thereby simplifying and reducing to a minimum the cost of such fastenings, and by use

of the shell in its own hole insuring the right size and depth hole, perfect fit, most workmanlike, durable, efficient and economic results.

To this end my invention consists in the 55 novel construction, arrangement and combination of parts herein shown and described, and more particularly pointed out in the claims.

60 In the drawings, wherein like reference characters indicate like or corresponding parts,

Figure 1 is a sectional view through a two part drill, which drill may after be used as 65 an expansion shell;

Fig. 2 is a similar view of the two sections separated with a bolt and expander shown;

Fig. 3 is a sectional view taken substantially on line 3—3 of Fig. 2;

Fig. 4 is a sectional view illustrating a 70 half drill and an open end cast shell;

Fig. 5 is a similar view of a half drill and closed end cast shell;

Fig. 6 is an end view of the same;

Fig. 7 is an end view;

Fig. 8 is a view in elevation of a drill and chuck, a portion of the chuck being in cross section;

Fig. 9 is a view in elevation of a slightly 80 modified form of drill from that shown in Figs. 1 and 9;

Fig. 10 is a sectional view through the same, the parts separated slightly;

Fig. 11 is a sectional view particularly 85 illustrating a modified cast shell and expander;

Fig. 12 is a sectional view of the same with bolt and expander removed;

Fig. 13 is a sectional view taken substantially on line 14—14 of Fig. 12;

Fig. 14 is a view in elevation of a slightly 90 modified form of drill;

Fig. 15 is an end view of the same;

Fig. 16 is a sectional view of the same and 95 its coöoperating chuck;

Fig. 17 is a sectional view taken substantially on line 18—18 of Fig. 17;

Fig. 18 is an end view of a portion of the 100 chuck;

Fig. 19 is a view in elevation of the shell and bolt in use;

Fig. 20 is an end view of the shell and hole with expander arranged thereon;

Fig. 21 is a view in elevation of the bolt with expander formed theron;

5 Fig. 22 is a side view of the same;

Figs. 23, 24 and 25 illustrate a modified expander which may be secured on the bolt, the same being similar to the expander shown in Fig. 2;

10 Fig. 26 is a view in elevation showing the inside of a modified drill;

Fig. 27 is a view in elevation of the same, two parts being shown;

15 Fig. 28 is a similar view showing the same in the chuck, the chuck being partially shown in section;

Fig. 29 illustrates this type of drill in use as an expansion shell;

20 Fig. 30 illustrates a modified form of drill, the chuck being shown in section; and

Fig. 31 illustrates the same drill used as an anchoring drill shell carrying a flat hanger.

Referring to the drawings, particularly 25 Figs. 1 to 8, there is shown a two part shell drill and auxiliary parts, of a tapered end type, in which the tapered end projects beyond the face of the material drilled or in which the parts are permanently used.

30 This type is particularly adapted to use with round rod hangers for pipe, etc., and for use with bolts or bolts and nuts on fastenings where the projecting end will not interfere. Figs. 1 and 2 represent two drill 35 parts, which are provided with cutting teeth or edges 3, the cutting end being preferably slightly larger for clearance, as at 4. The parts are made of suitable material, in the preferred way and of the desired size.

40 The end opposite the cutting edges is preferably tapered as at 5—5, and I prefer to provide holes or notches 6 in each drill part which coincide, when the two drill parts are together, forming holes. The parts are 45 preferably cut away as at 7 so as to form inclined faces on the two parts. Referring to Fig. 8, 8 represents the head of a suitable chuck or holder having a shank 9, which chuck is recessed as at 10 so as to fit the 50 tapered end 5—5. The chuck head 8 is shown tubular as at 11 with an opening 12 through which the drillings may escape so that the same do not clog up the drill or require the drill to be removed for cleaning.

55 The chuck may be operated in any suitable manner, the same shown being substantially a reciprocating or percussion chuck which may be operated by a spring, compressed air, electric, hand or other suitable type of hammer. After using the parts as a drill, the same may be used, in conjunction with other suitable parts, as an expansion or anchor bolt. The number of holes which may be drilled with this shell 65 drill will vary according to the material

from which it is made and method of making, and according to material to be drilled. When made of a like grade of drill steel it will drill equally as many holes as other types of drills, and when made of cheaper material and case hardened will drill fewer holes. In either case the worn or used drill parts are used with auxiliary parts of cheaper construction, as permanent fastenings in the holes drilled. The odd holes thus drilled will exceed the number of drill parts in which case auxiliary or like parts of cheaper material and construction will be used, to the end that the drill parts make all necessary holes of the right size and in 80 combination with other cheaper parts be utilized as permanent fastenings in the most satisfactory and economical way. In Fig. 2 I have shown the two drill parts and a round hanger rod or bolt 15, upon which is arranged an expanding nut 17 having wedge shaped or tapered wings 18 arranged to engage the faces 7. Obviously, after the hole is drilled, the drill parts may then be placed on the bolt or rod upon which is the nut 17, and inserted in the hole. The wings 18 of nut 17 project beyond the end of nut 17 and are of such width and taper that when drill parts are together the wings extend beyond end 3 of the same, and when inserted in the hole will come in contact with the bottom of the hole first, the hole being a neat fit. Any further travel of drill parts in contact with the wings 18 will cause the parts to open or expand in contact with the walls of the hole, and a few blows of the hammer will be sufficient to drive the drill parts to the bottom of the hole. If rod or bolt 15, which is threaded through nut 17, is turned or screwed against the bottom of the hole, it causes a further wedging or expanding effect thus firmly locking the parts in the hole. Cutting away a portion to provide the faces 7—7 also provides a clearance space so that drillings may escape from the end into the tubular bore. In case the parts wedge in the chuck tightly, the insertion of a tool in holes 6 easily loosens the same for removal of the chuck.

110 In Fig. 4, 2 represents one of the drill parts and 21 one of the auxiliary or co-operating half shells of cheaper construction, for example, a cast part or pressed steel without the cutting teeth or edges. The half shell 21 may be formed with corrugations or rough surface 22 arranged to engage with the wall of the hole and with the inclined faces 23. The same is also shown with the extending part 24 at one side arranged to seat in the notch 6 of the drill part. It may be mentioned that the 115

part 24 is arranged only on one side of the shell, so that when two cast shells are employed, the extending part of one will engage in the notch of the other. The shell 5 25 shown in Fig. 5 is similar except that the end is closed by an extending part 26. In this type the rod or bolt 15 will screw against the closed end of the shell instead of against the bottom of the hole as previously described.

10 A modified form of drill is shown in Figs. 9, 10, 11 and 12, in which 28 represents the drill parts formed with continuous cutting edges similar to the drill previously described. In this case the inner walls are formed as at 32 and the inclined faces are omitted. As shown in Figs. 11, 12 and 13, however, the coöperating cast shell and expanding nut are modified. As shown, the shell 29, which if desired may be formed with the closed end portion 30, is formed with an inclined face 31. In this case the threaded bolt or rod 33 is provided with a nut 34, etc., preferably extending as at 35 25 and would screw against the bottom of the hole or closed end of the shell as previously described, and would travel the nut in such manner as to open or expand the parts in the hole. It is of course obvious that an auxiliary half shell similar to the drill part 30 may be used in conjunction with shell part 29 where holes drilled exceed the worn drill parts available.

Figs. 14 to 20 show a straight end or flush 35 type shell drill, slightly modified in construction but embodying the salient points of the drills previously described. This type is suitable for use with rod hangers, bolts, or bolts and nuts, on various fastenings where the projecting end of the shells previously mentioned would not be suitable. In operation this type drills a hole full length of the drill shell and when permanently set is flush with the face of the material drilled or in which it is used. Referring to these figures, 38 represents the drill parts formed with the inclined faces, but with cutting teeth or edges formed on the opposite end 40. The drill parts are also 40 shown with corrugations or ribs as at 41. The drill may be operated by means of a suitable chuck consisting of the part 44 having a shank 45 of suitable length. It should be understood that the chuck and shank are 45 operated by any suitable hammer or mechanism, as before mentioned. The chuck in this case is shown with an extending part 46 and with a sleeve 47, the sleeve being preferably maintained in place by a spring 48 50 or its equivalent, 49 being an outlet for the drillings. With this type of drill and chuck a hole may be drilled the full length of the drill shell, after which the shell may be reversed and used as an expansion shell, as 55 illustrated in Fig. 19. The sliding sleeve

47 and lugs 46 maintain the drill parts together in proper relation, but the sleeve yields when it comes in contact with the work. As shown in Fig. 19, 50 represents the work or ceiling and 51 a bolt which may 70 be provided with the wings 52 or the equivalent arranged to engage the inclined faces 42. In this case the part 53 to be fastened is maintained in place by bolt 51 and nut 54. It is believed that the construction will be 75 obvious.

Figs. 26 to 29 illustrate a lag screw type of drill shell 57, with tapered end 59, in which the tapered end 59 projects beyond the face of the material drilled or in which 80 the parts are permanently used. This type is used in conjunction with a lag screw which opens or expands the parts when screwed to place and at the same time fastens and maintains in position the part to be 85 held. It is also understood that this shell can be made flush type and operated with the chuck previously described for use with the flush type shell drills 15 to 21. Fig. 26 represents the drill parts formed with cutting edges or teeth 58 and with the tapered end 59 and holes or notches 60. The interior is preferably threaded as at 61, beginning with a full thread adjacent to the tapered end, which thread becomes shallower toward the cutting end 58 and runs out entirely just short of the end or cutting teeth, in such manner as to leave a round 90 straight hole of a diameter corresponding to the diameter of the lag screw at the root of the thread. This hole acts as a passage for drillings, and the diminishing thread in conjunction with the tapered screw causes the shell parts to open as the screw enters. A chuck 62 is arranged to operate the drill 95 shell.

Figs. 30 and 31 represent a square end projecting type of drill shell, to be used where it is desired to carry flat bar or wire hangers or ties. Referring to these figures, 110 67 represents the drill parts provided with the cutting teeth 68, and 69 represents the material which is the wall or ceiling to be drilled, and which will support or carry the hanger and part to be hung or fastened. The 115 drill is arranged to seat in a suitable chuck 70. The drill parts are cut away as shown at 71 forming notches into which lugs 73 project to prevent the drill parts turning in the chuck while operating. 72 represents 120 holes. After the hole is drilled the chuck is removed and the shell parts secured in place by inserting a core of lead 74 or equivalent material, and driving the same toward and against the end of the hole, thereby expanding the shell parts. A flat bar hanger 75 may be secured in place by means of a pin, bolt or equivalent 76 extending through the holes in the bar and through the holes 72.

125 It will be noted that all the drill shells 130

described are of two part construction, but it is understood that they may be of one, two or more parts, suitably split and arranged for expansion, as may be required for any particular purpose. Another advantage of this shell or core type of drill, which may be mentioned here, over other types of fluted or flat type drills commonly used, is that practically 50% of the material removed in drilling is in the form of a core which breaks off in short pieces as the drill progresses, whereas with the fluted or flat drill all material removed is crushed or pulverized, requiring that much more work in drilling. The various possible combinations and uses of the shell drill will be obvious to those skilled in the art from the disclosures herein given. It will also be readily seen that a much less weight of material is required in the shell drill than in present types in use, and that cost of manufacture will be less, considering drills of equal size. When made of like material the drill shell will drill as many holes as other drills, before its use as an expansion shell. The use of the drill shell as an expansion bolt after drilling its hole, permits of making them of cheap material and case hardening. Such shells will drill a limited number of holes depending upon the material drilled, but in such material as concrete, brick and stone commonly used in building construction, will in all cases drill its own hole and in most cases a number of holes sufficient to make its use with auxiliary parts economical. When made of cheaper material the form of the shell drill permits punching them from the bar and forming in a press, which means rapid production and low cost.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A drill comprising a plurality of cooperating similarly formed parts arranged together to provide a tubular shell, the parts at one end of the shell enlarged and provided with cutting teeth at the extreme end, said parts cut away at their juncture adjacent said end to provide substantially V-shaped recesses, the opposite end of said shell parts arranged for engagement with a cooperating chuck.
2. A drill comprising a tubular shell provided with a cutting edge at one end and arranged at the opposite end for engagement with a suitable chuck, said shell formed to coöperate with suitable means for expand-

ing the same, whereby the shell may be expanded to engage the walls of the drilled hole.

3. A device of the kind described comprising a plurality of parts constructed to coöperate to provide a tubular shell with cutting edges at one end, and means projecting into the shell for separating said parts at one end. 70

4. A drill comprising a tubular shell provided with a cutting face at one end and arranged at the opposite end for engagement with a suitable chuck, and means for expanding the shell in the drilled hole after 75 operation of the same as a drill. 80

5. A tubular drill of the kind described comprising a shell part formed with cutting edges at one end and arranged at the opposite end to coöperate with a suitable chuck, an expander arranged in said shell at one end, and means projecting to the exterior of the shell at the opposite end for actuating said expander, whereby the drill may be expanded in the drilled hole and retained therein to support said expander and projecting means. 85

6. In a device of the kind described and in combination, a shell drill provided with an opening therethrough, a bar projecting thereinto at one end, and means on said bar 90 for expanding the shell at the opposite end. 95

7. A tubular shell drill comprising a plurality of parts, a bar projecting thereinto from one end, and means on said bar for engaging the parts at their juncture and 100 expanding the shell thereat.

8. A combined drill and expanding anchor bolt shell comprising a tubular shell formed with cutting edges at one end and arranged at the opposite end to engage a suitable chuck, and means for expanding said parts at one end in the drilled hole comprising a bolt threaded at the end and projecting thereinto, and an adjustable nut on said bolt. 105

9. A shell drill of the kind described comprising a tubular shell formed with cutting edges at one end arranged at the opposite end to engage a suitable chuck, and means for expanding the shell after removal of 115 the chuck comprising a bolt projecting into the shell, and means on said bolt for expanding said shell parts.

10. A drill consisting of an expandible tubular shell provided with cutting teeth at one end and constructed with a taper at the opposite end. 120

11. A drill consisting of an expandible tubular shell provided with cutting teeth at one end and constructed at the opposite end 125 to engage a suitable chuck.

12. A drill comprising two similarly formed parts, each part having teeth at one end and tapered at the opposite end, and constructed to provide a tubular bore 130

through the parts, each part formed to co-operate with an expander, whereby the parts may be separated and separately used with a coöperating shell part and provide

5 an expansion shell.

13. An expandible drill shell comprising two similarly formed parts, constructed to assemble, for use as a drill, in the form of a tubular shell having cutting teeth or edges

10 formed on one end thereof and having the opposite end tapered to engage with a co-operating chuck, and means for expanding or wedging the said two parts in the hole drilled when using as a permanent anchor

15 or fastening.

14. A drill consisting of an expandible tubular shell provided with cutting means and provided with means for engaging a co-operating chuck.

15. A self-drilling expansion shell consisting of an expansible tubular shell provided with drilling edges, and constructed to engage a suitable chuck while drilling, and means for expanding the shell in the hole, said shell arranged for engagement with co-operating fastening devices.

16. A self-drilling expansion shell consisting of an expansible shell body part provided with drilling edges, and constructed for engagement with coöperating fastening devices.

In testimony whereof I have hereunto signed my name in the presence of two subscribing witnesses.

JOHN H. PHILLIPS.
